J. W. Gibbs, of Albany, N. Y.
Assignor to
Rathbone & Co. of same place.
Letters Patent, No. 1004, dated, May 11, 1858.

The schedule referred to in these Letters Patent and making part of the same.

To all whom it may concern:

Be it known that J. W. Gibbs, in the City of Albany, in the County of Albany, and State of New York, have invented or produced a new and original design for a parlor Stove, and I do hereby declare, that the following is a full and exact description of the same, reference being had to the accompanying drawings and to the letters of reference marked thereon.

Fig. 1. represents the Urn of said parlor Stove, I claim the ornaments forming the handles of said Urn and also the ornament forming the center or principle surface.

Fig. 2. represents the Top of said parlor Stove and I claim the ornament or ornaments running around the outer edge of said Top marked A, also the general ornamentation and configuration of the center or top surface, of said Top, the whole of these ornaments forming in combination an ornamental parlor Stove Top.

Fig. 3. represents the close front of said parlor Stove, I claim as original the ornament or ornaments running along the upper moulding or edge B, and also the ornaments placed on the corners C, of said front also the ornaments running along the base marked D, I also claim the center ornament marked E, the whole forming in combination an ornamental close front for the said parlor Stove.
